United States Patent Office.

E. R. SHEPARD, OF SCRANTON, PENNSYLVANIA.

Letters Patent No. 96,276, dated October 26, 1869; antedated October 16, 1869.

IMPROVEMENT IN COMPOUND RAILS.

The Schedule referred to in these Letters Patent and making part of the same.

To all whom it may concern:

Be it known that I, E. R. SHEPARD, of Scranton, Pennsylvania, have invented an Improvement in Compound Rails; and I do hereby declare the following to be a full, clear, and exact description of the same.

My invention consists of a rail in two sections, which are constructed, as fully set forth hereafter, so that the upper section may be inclined at any desired angle to the lower, may be reversed when necessary, and will always have a firm bearing whatever may be its position.

In order to enable others skilled in the art to make and use my invention, I will now proceed to describe its construction and operation, reference being had to the accompanying drawing, which forms a part of this specification, and in which—

Figure 1. is a transverse section of my improved compound rail;

Figure 2, a side view of the same; and

Figure 3, an end view of a compound rail of the ordinary form.

The rail is composed of two parts, namely, the upper portion, A, of steel or superior iron, and the lower portion, B, which may be of inferior iron or steel.

The upper portion of the rail consists of the head or tread a, and the rib b, which is rounded at the lower edge to a true circle, and the lower portion consists of a base, c, and a flange, d, the outer face of the latter, in the present instance, being inclined and the inner face vertical.

In the base, at the inner side of the flange d, is a rounded recess, e, corresponding to the rounded lower edge of the rib b, which rests and turns in the said recess, as described hereafter.

The upper edge, z, of the flange d is inclined, to correspond to the adjacent inclined under face of the head a, and the rib b increases in width from the point where it joins the head a to the rounded edge, so that both sides are inclined in respect to a line, x-y, drawn through the centre of the portion A, fig. 1.

The two portions of the rail are secured together by bolts, C, which pass through openings in the rib b and flange d, the heads of the bolts being adapted to the inclined outer side of the rib b and the nuts g, bearing on slotted washers, h, which intervene between the nuts and the flange d.

In a longitudinal groove, o, which crosses the threads of each bolt, fits a pin, F, having a head at the outer end, and at the upper side a sharp-edged projection, n, which penetrates the nut and prevents it from turning.

Should the two portions of the rail be brought together, so as to loosen the bolt, the wedge h will fall and fill the increased space between the nut and the

side of the flange d, thus preventing any rattling or longitudinal movement of the bolt.

Inasmuch as the devices for securing the nut and tightening the bolt form the subject of another application for Letters Patent, no further reference will be made to them here.

The flange d is of such a length that the head a will find a bearing on the upper edge z, before the portion A is inclined sufficiently for the side of its rib to be brought in contact with the inner face of the flange. The upper portion of the rail, therefore, as it bears on the lower portion at two points only, will yield when pressure is applied by the bolts between these two points, and, having a constant tendency to resume its original position, will be pressed firmly on its bearings, and will not become loosened and rattle should the pressure applied by the bolts be slightly reduced, or should the parts of the rail contract in consequence of a decrease of temperature.

In a compound rail having a vertical rib beneath the head, the treads of car-wheels, owing to the inclination of the same, bear upon the head of the rail at one side of a vertical line drawn through the centre of the bearing of the rib, fig. 3, the tendency of the wheel, therefore, is to force inward the upper from the lower portion of the rail, drawing out the bolts.

It will be seen that in my improved rail, the portion B is inclined outward to such an extent that the portion of the head a which forms the bearing for the tread of the wheel is on the same vertical line, x-y, fig. 1, as the lower bearing of the rib b; there is, therefore, little or no pressure upon the rail tending to force it laterally in either direction, so as to separate the two parts of the same and rupture the fastening-devices.

Owing to the rounded form of the lower edge of the rib b and of the recess or socket e, a bearing-surface of the same extent and solidity is insured, whatever may be the inclination imparted to the portion A of the rail, this being a very important feature, as no other form of base will give a full bearing when the inclination of the upper section of the rail is altered.

One of the principal advantages resulting from this rounding of the edge of the rib and its socket, is that the upper portion A of the rail may be reversed.

It will be seen, that owing to the inclination of the portion A, the treads of the wheels bear on the face of the tread a at one side only of the central line x-y. When, therefore, this side is worn and battered, the reversing of the portion A will present a new and uninjured surface to the wheel.

I claim as my invention, and desire to secure by Letters Patent—

1. A compound rail, consisting of a lower permanent portion, B, and an upper detachable and reversible portion, A, adjusted to an inclined position on the base, substantially as and for the purpose described.

2. A compound rail, consisting of two portions, A and B, the latter having a base, a flange, and a recess, *e*, rounded to the arc of a circle, and the former being reversible, and having a head, *a*, and a flange, *b*, the

lower edge of which is rounded to fit the recess *e*, substantially as and for the purpose described.

In testimony whereof, I have signed my name to this specification, in the presence of two subscribing witnesses.

E. R. SHEPARD.
